UNITED STATES PATENT OFFICE.

PHILIP YEAGER, OF ORAN, IOWA.

ROAD-GRADER.

1,155,862.

Specification of Letters Patent.

Patented Oct. 5, 1915.

Application filed March 22, 1915. Serial No. 16,117.

To all whom it may concern:

Be it known that I, PHILIP YEAGER, a citizen of the United States, residing at Oran, in the county of Fayette and State 5 of Iowa, have invented a new and useful Road-Grader, of which the following is a specification.

This invention has reference to road graders, and its object is to provide a grader 10 whereby a road surface may be smoothed by means of a diagonally set scraping blade, while all tendency of the scraping blade to move laterally of the line of travel is effectively counteracted.

15 In accordance with the present invention there is provided a scraper or scraping blade capable of being set at different angles to the line of draft so as to extend crosswise of the direction of travel in a manner to cause dirt caught by the scraper to progress 20 laterally of the line of travel, thus smoothing the road surface and filling all ruts and depositing surplus dirt to one side of the portion of the road bed treated by the 25 scraper.

Because of the diagonal set of the scraper there is a continual tendency to shift the scraper blade laterally of the line of travel. To overcome this tendency and also to more 30 or less loosen the surface of the road bed where treated by the scraper and to furthermore provide a support for the scraper whereby its depth of cut may be regulated, the machine has in front of the scraper a 35 laterally extended series of disks all concaved in one direction so that the disks by the engagement of their peripheral portions with the road bed counteract or oppose any tendency of the scraper to travel sidewise 40 of the main direction of travel.

The invention also contemplates numerous features of improvement in the adjustment of the scraper to the line of travel, means coacting with the disks to uphold the 45 scraper to produce any desired depth of cut, and a seat so arranged that the driver of the vehicle may readily control it without inconvenience despite considerable variations in the relation of the holding disks to 50 the scraper blade.

The invention will be best understood from a consideration of the following detailed description, taken in connection with the accompanying drawings forming a part 55 of this specification, with the further understanding that while the drawings show a

practical form of the invention, the latter is not confined to any strict conformity with the showing of the drawings, but may be changed and modified so long as such 60 changes and modifications mark no material departure from the salient features of the invention.

In the drawings:—Figure 1 is a plan view of a scraper constructed in accordance with 65 the present invention. Fig. 2 is a side elevation of the scraper. Fig. 3 is a longitudinal section, in most part a central longitudinal section, of the scraper with some parts remote from the general plane of the section also shown in longitudinal section. Fig. 4 is a longitudinal section of the disk member. Fig. 5 is a rear view of one end 70 of the scraper blade. Fig. 6 is a detail perspective view showing the manner of connecting a supporting and adjusting arc to the series of concave disks. Fig. 7 is a detail perspective view showing the connection 75 of the scraper holding frame with the body of the scraper.

80 Referring to the drawings, there is shown an elongated scraper 1 concaved on one face with the top and bottom edges of the scraper substantially parallel. At one end the scraper is formed with a share or tongue 85 2. Such end of the scraper is in practice usually the forward end since the scraper is customarily set at an angle to the line of draft so that dirt which is gathered by the scraper blade in the usual manner is caused 90 to progress from the forward end of the scraper across the line of travel to the rear end of the scraper from which the accumulated dirt readily escapes. Such a scraper blade will level off a road bed, cutting down 95 the ridges and depositing the gathered dirt into the ruts, so that where passed over by the scraper the road surface becomes sensibly smooth or level from side to side.

100 Secured to the back of the scraper blade 1 by rivets 3 or otherwise are straps 4, there being a strap near each end of the scraper. Each strap is extended above the upper edge of the scraper and is there bifurcated and perforated as shown at 5. Connected to the 105 bifurcated end 5 of each strap 4 is a bar 6 having a series of holes 7 therethrough for the passage of a bolt 8 constituting the means for connecting the bar 6 to the end 5 of the strap 4. The bar 6 terminates at one 110 end in a sleeve 9 constituting a journal support for a standard 10 held to the sleeve 9

by set collars 11 on opposite sides, these collars being held in place by respective set screws 12. Each standard 10 is substantially upright and carries at its lower end a 5 caster wheel 13 in trailing relation to the scraper 1.

Near opposite ends of the scraper and preferably at the points backed up by the straps 4 are yokes or eyes 14 projecting on 10 the front or concave face of the scraper about midway of the height thereof. Each yoke 14 may be in the form of a U bolt with the legs extending through the scraper blade 1 and through a strap plate 15 at the rear of 15 the blade with the strap plate extending over the strap 4, or any other arrangement suitable for the purpose may be provided. Connected to the bolts or yokes 14 are the respective ends of a frame 16 in the form of 20 an elongated bar, preferably though not necessarily a flat bar, having a curved front end 17 provided with a series of spaced perforations 18. The curved end 17 is in the form of an arc for a purpose to be described. Each bar 6 has the end remote 25 from the sleeve 9 preferably bent toward the frame 16 and terminates in a tongue 19 extending through a perforation 20 in a suitable part of the frame 16, so that the 30 bars 6 participate in any movements of the frame 16 causing the caster wheels 13 to rise and fall in accordance with the movements of the frame 16. There is also provided a series of concave disks 21 mounted on a rod 35 or spindle 22 to turn freely thereon and held in spaced relation one to the other by spacer sleeves 23 on the rod 22. The rod 22 is mounted at the ends in the corresponding ends of legs 24 of a yoke frame 25, the said 40 frame 25 being normally in overriding relation to the series of disks and the lower ends of the legs 25 are perforated as shown at 45 in Fig. 6 for the passage of the rod 22.

Each leg 24 of the frame 25 near the passage 26 and on one side of the upright center line of the leg has a perforation 27 therethrough in which there is lodged a corresponding hooked end 28 of a curved bar 29 conforming in curvature to the curved end 50 17 of the frame 16. This bar may have perforations matching the perforations 18 of the frame 16, so that the bar 29 and the curved portion 17 of the bar 16 may be connected together by a bolt 30 or a suitable 55 number of such bolts, if desirable.

Connected to the series of disks 21 intermediate of the length of said series is a pole 31 formed at the end connected to the series of disks with a yoke strap 32 encircling an appropriate one of the spacer sleeves 23. The bolt 30 besides traversing a perforation 18 of the frame 16 and a corresponding perforation of the frame 29 also traverses the pole 31 at an appropriate 65 point.

Connected at one end to the pole 31 by a bolt 33 is a strap 34 having the other end formed into a hook 35 adapted to engage in a perforation 36 near one long edge of the yoke 25. The other long edge of this yoke 70 25 has other perforations 37 formed therein and engaging in any one of these perforations is a hook end 38 formed on a plate 39 appropriately bent or shaped to rest upon the top edge of the scraper blade 1. Mounted on the plate 39 is a seat standard 40 carrying a seat 41 which may conform to seats as usually provided in machines of the character of the present invention. The plate 39 at the end remote from the hook 38 is 75 laterally expanded so as to provide a broad bearing surface where resting upon the upper edge of the scraper 1.

In the operation of the device the curved bar 29 being connected to the pole 31 at an intermediate point and at the ends to the legs 24 of the yoke 25, the series of concave disk rollers 21 have their axes of rotation substantially perpendicular to the length of the pole 31 and, therefore, to the direction 90 of travel of the machine. The disk rollers 21 all face in one direction with the concave faces directed toward that side of the machine where the forward end of the scraper 1 is located. The scraper 1 is set at any 95 desired angle to the line of draft, which angle is usually a small angle, by arranging the bolt 30 through that one of the holes 18 which will hold the frame 16 and the scraper 1 carried thereby at the angle desired. 100

The scraper 1 is supported in front of its cutting edge by the laterally extended series of disks 21 and is supported at the rear of its cutting edge by the caster wheels 13, 105 which latter are arranged near the ends of the scraper.

The position of the stems or standards of the caster wheels is determined by the set collars 11 and the depth of cut of the scraper 110 is readily determined by the position of the caster wheels which if lowered decrease the depth of cut of the scraper and if raised increase such depth of cut.

The degree of inclination of the scraper 1 115 with reference to the line of draft is readily changed as desired by taking out the bolt 30 and moving the frame 16, so that another passage 18 is brought into line with the customary position of the bolt 30 through the 120 pole 31, the other parts of the mechanism readily accommodating themselves to the changed relation thus brought about. The seat supporting plate 39 permits such adjustment within reasonable range. For 125 some purposes, as, for instance, weighting the scraper blade, one or more plates 39 may be provided and such plates are hooked in the other perforations 37. However the scraper blade may be related to the line of 130

draft, there is, except when the scraper blade is perpendicular to the line of draft, a tendency of the scraper blade to move laterally of the line of draft toward the side of the machine occupied by the forward end of the inclined blade. This tendency is wholly overcome by the concave disks 21 of which one or more will bite into the road bed and so counteract the sidewise tendency. Moreover, these disks attack the rough surface of the roadbed to cut and loosen it, whereupon the scraper in engaging such loosened surface meets less resistance than would be the case were the surface of the road wholly untreated before being reached by the scraper. So far as the action of the scraper blade is concerned it need not differ from scraper blades as ordinarily constructed, for the scraper blade like other blades of like character smooths off the high places and directs the loosened dirt into ruts and the like, wherefore the road bed after being traversed by the structure is markedly smooth and free from either protuberances or depressions.

The perforations 7 permit the tilting of the scraper blade on the yokes or eyes 14 toward the upright position which may be found to be desirable where the character of the surface is liable to cause clogging on the lower edge of the scraper if in too slanting a position.

What is claimed is:—

1. A road grader having a scraping blade, a series of concave disks with the concave faces of the disks all presented toward that side of the machine corresponding to the forward end of the scraper blade, and said series of disks being of a lateral extent to include the greater portion of the length of the scraper blade and constituting the sole support for that portion of the machine in advance of the scraper blade, draft means for the grader in fixed perpendicular relation to the axis of the series of disks, and connections between the series of disks and the scraper adjustable with relation to the series of disks to vary the inclination of the scraper with respect to the line of draft.

2. A road grader having a scraping blade, a laterally extended series of concave disks with the concave faces all presented toward that side of the machine corresponding to the forward end of the scraper blade, and said disks constituting the sole support for the grader in advance of the blade, a draft pole connected to the mid portion of the series of disks and to the ends of the series in substantially perpendicular relation to the longitudinal axis of the series of disks, and connections between that portion of the grader comprising the pole and series of disks and that portion of the grader including the scraping blade for the adjustment of the angle of the scraping blade with re-

lation to the line of draft with the longitudinal axis of the series of disks in constant perpendicular relation to the line of draft.

3. A road grader comprising a scraper blade, supporting wheels for the scraper 70 blade in trailing relation thereto, a laterally extended series of concave disks with the concave faces all presented toward that side of the machine corresponding to the forward end of the scraper blade, a draft pole and 75 connections between the latter and the series of disks for maintaining the latter in constant perpendicular relation to the pole and the line of draft, said series of disks constituting the sole support for that portion of 80 the grader in advance of the scraper blade, and connections between the series of disks and the scraper blade with said connections adjustable to vary the diagonal relation of the blade to the line of travel of the grader. 85

4. A road grader provided with scraping means, a frame connected to the scraping means, a series of rotating members arranged transversely to the line of travel of the scraper and constituting means for 90 counteracting side movement of the scraper, a frame connected to said series of rotating members, and draft means connected to the series of rotating members and to the frame thereof, the frame connected to the series of 95 rotating members and the frame connected to the scraping means being correspondingly curved and provided with means for connecting them together and to the draft means whereby the angular relation of the 100 scraper to the line of draft may be adjusted.

5. A road grader comprising a scraping member, a series of supporting disks and a carrying frame therefor arranged transversely of the line of travel of the scraper, 105 draft means connected to the series of disks, connecting means between the scraper and draft means for varying the angular relation of the scraper to the line of draft, supporting rollers for the scraper means in 110 trailing relation thereto, and a seat support connected to the frame of the series of disks and extending to and resting upon the scraper and movable with relation to the latter to accommodate the seat support to different angular positions of the scraping means. 115

6. A road grader comprising an elongated scraping blade, a frame connected thereto and extending forwardly from the blade and having its forward portion curved about an axis, a series of disks each concave on one face and all having the concave faces presented toward the same side of the scraper, a connecting frame for the series of disks, 120 another frame connected to the connecting frame and curved in conformity with the frame connected to the scraper blade, a draft member connected to the series of disks and to the curved portions of the frames connect- 125 130

ed to the scraper blade and disks, respectively, with the frame connected to the scraper blade adjustable with relation to the draft means to vary the angle of the 5 scraper blade to the line of draft, caster wheels connected to the scraper blade at the rear thereof and adjustable up and down with relation to the scraper blade to vary its depth of cut, and a seat and support, said 10 support being connected to the frame carrying the disks and resting upon the top edge of the scraper blade.

7. A road grader comprising an elongated scraping blade, a frame connected thereto 15 and extending forwardly from the blade and having its forward portion curved about an axis, a series of disks each concave on one face and all having the concave faces presented toward the same side of the scraper, 20 a connecting frame for the series of disks, another frame connected to the scraper blade, a draft member connected to the series of disks and to the curved portions of

the frames connected to the scraper blade and disks, respectively, with the frame connected to the scraper blade adjustable with relation to the draft means to vary the angle of the scraper blade to the line of draft, 25 caster wheels connected to the scraper blade at the rear thereof and adjustable up and down with relation to the scraper blade to vary its depth of cut, and a seat and support, said support being connected to the frame carrying the disks and resting upon the top edge of the scraper blade, the draft means 30 and seat being adjustable with relation to the frame carrying the disks in a direction transversely of the line of draft.

In testimony, that I claim the foregoing as my own, I have hereto affixed my signature in the presence of two witnesses.

PHILIP YEAGER.
